(57) **CLAIM**

The ornamental design for a light, as shown and described.

DESCRIPTION

FIG. 1 is a front, top and right side perspective view of a light, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is a front perspective view showing the upper portion of the light in an alternate condition of use, with the ground stake portion not in use.

The broken lines shown in the drawings illustrate portions of the light that form no part of the claimed design.
